UNITED STATES PATENT OFFICE

WILLIAM J. McMARLIN AND LESTER S. GUNDERMAN, OF PITTSBURGH, PENNSYLVANIA

MECHANICAL EXERCISING DEVICE OF THE MOTOR DRIVEN TYPE

Application filed October 4, 1928. Serial No. 310,224.

This invention relates to exercising devices of the motor driven type, and is directed to an exercising device of this character provided with a footrest by means of which the 5 operator may vibrate his feet and lower limbs.

This invention is especially applicable to exercising devices of the type shown in the copending application of Harry E. McCoy, 10 Serial No. 297,827, filed August 6, 1928. In the said McCoy application, there is disclosed an exercising device of the motor driven type wherein a horizontally extending arm is oscillated about a vertical pivot by means of an 15 eccentric at the end of a motor shaft, which eccentric bears against a right angle extension on said horizontal arm. According to a preferred embodiment of our invention, we provide a footrest which is applied directly 20 to this arm and which is preferably in the nature of an attachment, the arrangement being such that when the arm is oscillated, the footrest moves with the arm, and in addition, a vertical reciprocating or vibrating movement 25 is transmitted to the footrest.

The invention may be readily understood by reference to the accompanying drawings which show a preferred embodiment of our invention and, in which

30 Figure 1 is a plan view of an exercising device of the McCoy type having the footrest applied thereto;

Figure 2 is a side view, partly in section and partly in elevation, of the machine 35 shown in Figure 1;

Figure 3 represents a longitudinal vertical section along the footrest and oscillating arm, as showing the manner of connection between the arm and the footrest; and

40 Figure 4 is a view generally similar to Figure 3, the ends of the arm and the footrest being broken away, this view showing a slightly modified arrangement wherein a greater amount of vertical movement is imparted to the footrest.

In the drawings 2 designates a base which supports a vertical pin 3. The pin 3 passes through the middle of a horizontal bar or arm 4. Extending rearwardly from the middle of the arm 4 is an extension 5 having

a bearing therein which cooperates with an eccentric at the end of the shaft 6 of a motor 7. The motor 7 is also carried on the base 2. The eccentric mechanism is disclosed in the said application of Harry E. McCoy, Serial 55 No. 297,827, and forms no part of the present invention. For convenience in understanding the operation, however, this is shown to some extent in Figures 1 and 2. There is provided on the end of the shaft 6 an eccentric disc 6^a operating within a ball ring 6^b, a series of ball-bearings 6^c being confined between the periphery of the disc 6^a and the ring 6^b. By reason of this arrangement the disc 6^a rotates within the ring 6^b, and the ring 6^b is displaced laterally and vertically with the rotation of the eccentric. The housing 5 is provided with vertical wear plates 5^a against which the outside of the ring bears, the width of the housing being such that the 60 outside of the ring is in contact with the wear strips at all times. There is sufficient vertical clearance, however, so as to permit the ring 6^b to slide up and down on the wear strips. By reason of this arrangement the 65 lateral displacement of the eccentric is transmitted to the vibrating arm to oscillate it in a horizontal plane while the vertical component of its movement is not transmitted to the vibrating arm. On the arm 4 at each 70 side of the central pin 3 are one or more hooks 8 to which straps (not shown) can be attached in the use of the exercising device.

According to the present invention, we provide a footrest in the form of a plate 9 which 75 sets over the bar 4. On the underside of the plate 9 are downwardly extending pins 10. There are at least two of these pins 10, one at each side of the center, and they are slidably received in openings 11, provided in the 80 bar 4 for their reception. On the underside of the footrest 9, at the middle thereof, there is preferably provided a downwardly extending lug 12 with a pad or block of rubber or other nonmetallic substance 13 therein. The 85 rubber block 13 is adapted to rest on the top of the rearward extension 5 of the oscillating cross bar and to steady the footrest to some extent.

In the arrangement shown in Figure 3, the 100

top of the pin 3 is provided with inclined surfaces 14, which surfaces are also shown in Figure 2. Depending from the underface of the plate 9 are lugs 15. There is one of these lugs at each side of the center of the pin 3, and the lowermost ends of the lugs are adapted to rest on the head of this pin so as to engage the inclined surfaces 14.

In the operation of the device, the bar 4 is oscillated about the pin 3 upon operation of the motor 7. This oscillating movement is transmitted to the footrest 9 through the pins 10. The pin 3 is stationary with respect to the cross bar 4 and the footrest 9 so that as the footrest 9 oscillates, the lugs 15 ride up and down on the inclined surfaces 14 on the head of the stationary pin 3. In this way, a vibrating movement up and down is transmitted to the footrest while the footrest is oscillating in a horizontal plane.

In the arrangement shown in Figure 3, the lugs 15 are relatively close to the center of movement of the bar 4 and of the footrest so that the travel on the inclined surfaces 14 is relatively short and the vibrating movement consequently is very light. In order to secure more effective vibration of the footrest, the arrangement shown in Figure 4 may be used.

In the arrangement shown in Figure 4, 20 designates the pin corresponding to the pin 3 and 21 is the oscillating cross bar or arm. The footrest is designated as 22 and on the undersurface thereof are pins 23 corresponding to the pins 10 of the structure previously described. Depending from the undersurface of the footrest 22 are spaced apart lugs 24, one of these lugs being at each side of the vertical axis of the pin 20. Passing through the head 25 of the pin 20 is a rod 26.

The arrangement is such that when the bar 21 oscillates about the pin 20, moving the footrest 22 with it, the lugs 24 will strike the ends of the rod 26 and thus effect a vertical vibration of the footrest. The ends of the lugs 24 are rounded so as to ride over the top of the rod 26, the rod 26 taking the place of the inclined cam surfaces 14 of the construction shown in Figures 2 and 3. The advantage of this arrangement is that the lugs 24 are further away from the center of oscillation so that the arc of movement is relatively greater and a correspondingly greater vertical movement can be imparted to the footrest.

Exercising devices of the motor driven type, now on the market, do not provide any arrangement by means of which the user can sit on a chair and impart a vibrating motion to the feet and lower limbs. According to the present invention, a machine is provided wherein this can be done and wherein the vibration is in two directions, thus increasing the stimulating action of devices of this character. The invention is preferably con-

structed as an attachment for the McCoy type of exerciser, but obviously we do not limit ourselves to the use of the invention in connection with any particular type of machine and the invention may be variously modified to adapt it to different types of exercising units of this character.

We claim as our invention:

1. In a mechanical exercising device, a vibrating member supported for movement in a horizontal plane, a footrest mounted on said vibrating member for movement therewith, and means for imparting a vibration in a vertical direction to said footrest upon movement thereof in a horizontal plane.

2. In a mechanical exercising device, a footrest, means for moving the footrest back and forth through an arc in a horizontal direction, and means for simultaneously moving the footrest up and down when the footrest is moved back and forth.

3. In a mechanical exercising device, a horizontally extending bar mounted on a vertical pivot, means for oscillating the bar, and a footrest removably carried on the bar.

4. In a mechanical exercising device, a horizontally extending bar, a vertical pin about which the bar oscillates, means for oscillating the bar, a footrest on the bar movable up and down relatively thereto, and cooperating means on the pin and the footrest for imparting vertical movement to the footrest upon oscillation of the bar.

5. In a mechanical exercising device, a horizontally extending arm, a stationary pin about which the bar oscillates, means for oscillating the bar, a footrest supported above the bar having pins thereon slidably received in openings in the bar, and cooperating means on the footrest and said stationary pin for effecting a vertical movement of the footrest upon oscillation of the bar.

6. In a mechanical exercising device, a horizontally extending bar having spaced openings therein, a stationary pin about which the bar oscillates, a right angle extension on the bar, means cooperating with the extension for oscillating the bar, a footrest mounted on the bar and having pins thereon slidably received in the openings in the bar, and cooperating means on the stationary pin and the bottom of the footrest for imparting a vertical vibrating movement to the footrest upon oscillation of the bar, and a pad on the underside of the footrest engaging the top of said right angle extension on the bar.

7. In a mechanical exercising device, a vibrating element movable in a horizontal plane about a vertical axis, means for vibrating the element, said element having a wide surface at each side of the axis adapted to provide a footrest.

8. In a mechanical exercising device, a vibrating element movable in a horizontal plane about a vertical axis, means for vibrat-

ing the element, said element having a wide surface at each side of the axis adapted to provide a footrest, and means below the element and shielded by the element to which straps may be connected.

5 9. In a mechanical exercising device, a vibrating member adapted to oscillate in a horizontal plane about a vertical axis, means for vibrating said member, said member having a relatively wide surface with a forward inclination adapted to provide a footrest, the inclination permitting the user to brace his feet on the footrest while seated on a chair.

10 15 In testimony whereof we have hereunto set our hands.

WILLIAM J. McMARLIN.
